V. E. KIRK

CUFF PROTECTOR

Filed April 16, 1923

FIG. 2

FIG. 3

VOLNEY E. KIRK
INVENTOR.

FIG. 4

BY R. W. Smith
ATTORNEY

UNITED STATES PATENT OFFICE.

VOLNEY E. KIRK, OF LOS ANGELES, CALIFORNIA.

CUFF PROTECTOR.

Application filed April 16, 1923. Serial No. 632,303.

To all whom it may concern:

Be it known that I, VOLNEY E. KIRK, a citizen of the United States, residing at Los Angeles, county of Los Angeles, State of California, have invented new and useful Improvements in Cuff Protectors, of which the following is a specification.

It is the object of this invention to provide a cuff protector which may be readily placed 10 in position around the wrist and over the cuff of the shirt so as to prevent soiling of the latter, and which may be as quickly and easily removed when not in use.

It is a further object of the invention to 15 provide a protector which may be adjusted to wrists of different size, and which if desired may be taken apart when not in use, so as to readily fit in the pocket, or form a compact package for shipment or storage of 20 said protectors.

It is a still further object of the invention to provide a protector which when in use, will positively engage the upper edge of the 25 cuff to properly position the device over the cuff and around the wrist, and which is also provided with means adapted to engage the coat sleeve when the coat is worn, thereby affording additional means for holding the 30 protector in proper position.

It is a still further object of the invention to provide a wrist encircling protector having 35 overlapping meeting edges provided with means for connecting said meeting edges between the upper and lower edges of the same, the upper edge of the device having means tending to expand the same and thereby pivot the meeting edges of the protector at their fastening connection so as to contract the lower edge of the device and 40 form a snug fit around the wrist.

It is a still further object of the invention to provide a protector of extremely simple construction, the means for expanding the upper edge of the device forming an integral part of stiffening means for the overlapping meeting edges of the protector, with the fastening means for said meeting edges also forming an integral part of said stiffening means.

Further objects of the invention will be readily understood from the following description of the accompanying drawings, in which:

Fig. 1 is a perspective view showing the cuff protector in use. 55

Fig. 2 is a front elevation of the protector showing the same removed from a cuff.

Figs. 3 and 4 are sections on the lines 3—3 and 4—4 of Fig. 2.

Fig. 5 is a front elevation showing a modified form of the protector. 60

Fig. 6 is a detail section on the line 6—6 of Fig. 5.

Fig. 7 is a fragmentary front elevation, partly broken away, showing a still further 65 modification of the invention.

I have illustrated the improved cuff protector mounted upon the cuff A of a shirt sleeve B, the cuff forming a usual ridge C at its upper edge where it is sewed to the 70 shirt sleeve in the case of a single straight cuff, and where it is folded back upon itself in the case of a double reversely folded cuff. The sleeve of the coat worn over the shirt is shown at D. 75

The protector comprises a band 1 of suitable pliable or elastic material, preferably of fabric, and of a length adapted to be received snugly around the wrist over the cuff inside of the coat sleeve, with the meeting 80 edges of the band overlapping, the band being of a width somewhat greater than that of a cuff, so as to extend from the upper edge of the latter beyond the lower edge thereof and down over the wrist beyond the 85 end of the coat sleeve.

An open spring ring 2, preferably shaped to conform to the wrist, is fixed to the inner side of the upper edge of band 1, as by positioning said ring in a tunnel formed 90 by a hem 3 at the edge of the band, and said ring is provided with inwardly bent, circumferentially spaced offsets forming projections 4, extending through suitable slots in the hem 3. 95

In the form of the invention illustrated in Fig. 2, ring 2 is permanently fixed in hem 3, and is provided with end extensions 5 extending the length of the meeting edges of band 1, and received in tunnels at said meeting edges, formed by hems 6; while in the form of the invention shown in Fig. 5, ring 100 2 is removable from its tunnel, as by making hem 3 of a width to permit the ring with its offsets 4 to be readily slid through said 105 tunnel.

Means are provided for connecting the meeting edges of the wrist encircling band, said means being preferably adjustable to adapt the protector to wrists of different size.

In the form of the invention illustrated in Fig. 2, the connecting means are shown as cooperating separable fastening connections made a part of extensions 5. As an instance 10 of this arrangement one of the extensions 5 is formed with an offset forming a hook 7, and the other extension includes an offset forming a plurality of loops 8, one beyond another along the length of band 1 and adapted to have any one of said loops engaged by hook 7.

The connecting means for the meeting edges of band 1, as shown in Fig. 5, is an elastic adjustable connection comprising a 20 hook 7' at one of said meeting edges, and an elastic tape 9 fixed to the band adjacent the other meeting edge thereof, and carrying an eye 8' adapted to be engaged by said hook.

25 The fastening connection for the meeting edges of band 1 is positioned medially of the length of said meeting edges, so that when the device is received around the wrist over the shirt cuff, and said fastening means are connected, the spring ring 2 will tend to expand and thereby pivot the meeting edges of the band at their fastening connection, as shown in Fig. 1, in order to overlap the lower ends of said meeting edges and 30 contract the lower end of the protector around the wrist.

The protector is positioned for use with ring 2 at the upper edge of cuff A, so that offsets 4 will impinge against the ridge C to 40 prevent the device sliding downwardly upon the wrist, the lower end of the protector extending beyond the lower end of the cuff and fitting snugly around the wrist as previously described.

45 The device is thus held in position by projections 4, whether or not the coat is worn, and when the coat is on the protector is received inside the sleeve D and is adapted to extend beyond the lower end thereof, and is 50 preferably provided with means for engaging the coat sleeve to further insure proper positioning of the protector.

55 As an instance of this arrangement a spring clip is fixed upon the band 1 adjacent its lower end and at a point which will be beyond the end of the coat sleeve, said clip comprising a base 14 having a spring finger 15 extending toward the upper end of the protector and adapted to be clipped over the edge of the coat sleeve, when the device 60 is in place.

In Fig. 7 I have shown a still further modification of the invention, adapted to expedite the proper positioning of the protector inside of the coat sleeve and around

the shirt cuff. In this construction, the ring received in the tunnel formed by hem 3, is made in two parts 2' which are pivoted as shown at 12, so that they may be swung downwardly toward one another. A spring 70 13 is fixed to the underside of one of the ring sections and is adapted to abut against the underside of the other ring section, so as to normally swing the ring sections into alignment and thereby form the expandible 75 ring for the upper end of the protector.

In placing the protector as thus described, around the cuff and inside of the coat sleeve, ring ends 2' are swung downwardly against the action of spring 13, and the apex of the 80 angular arrangement formed by the pivotal connection between the ring ends, is slipped inside the coat sleeve until it is at the upper end of the shirt cuff. The ring sections are then released so that spring 13 may swing 85 the same into alignment and thereby draw said ring sections and the upper end of the protector inside the coat sleeve, in order to properly position the device for impingement of projections 4 against the ridge C at 90 the upper end of the cuff.

It will be apparent that various changes may be made in the construction, combination, and arrangement of parts as thus described, without departing from the spirit 95 of the invention.

What is claimed is:

1. A cuff protector comprising a band adapted to encircle the wrist and be received over the shirt cuff and having means for connecting the meeting edges of said band between the upper and lower edges thereof, and means tending to expand the upper edge of said wrist encircling band so as to pivot its meeting edges at their fastening connection and thereby contract the lower edge of the band around the wrist.

2. A cuff protector comprising a band adapted to encircle the wrist and be received over the shirt cuff and having means for connecting the meeting edges of said band between the upper and lower edges thereof, and means tending to expand the upper edge of said wrist encircling band so as to pivot its meeting edges at their fastening connection and thereby contract the lower edge of the band around the wrist, said expanding means having an inwardly extending projection adapted to engage the upper edge of the cuff for holding the protector in place.

3. A cuff protector comprising a band adapted to encircle the wrist over the cuff of a shirt with the upper edge of said band substantially in alignment with the junction of said cuff with the shirt sleeve and the 125 lower edge of said band extending downwardly beyond the lower edge of said cuff, said band having a tunnel at the upper edge thereof provided with an opening in the inner face of the same, and a spring ring re- 130

ceived in said tunnel and having an inwardly extending projection protruding through said opening and adapted to impinge against the ridge formed at the junction of said cuff and shirt sleeve for holding said protector in place.

4. A cuff protector comprising a band adapted to encircle the wrist and be received over the shirt cuff and a spring ring fixed to the upper edge of said band, said ring comprising pivoted sections adapted to be swung toward one another and the lower edge of said band, and a spring adapted to normally swing said ring sections into transverse alinement.
5. A cuff protector comprising a band adapted to encircle the wrist and be received over the shirt cuff, and having means for connecting the meeting edges of said band intermediate of the upper and lower edges

thereof, whereby said meeting edges of the band may pivot at their fastening connection for contracting the lower edge of said band around the wrist, said band having an inwardly extending projection at its upper edge adapted to engage the upper edge of the cuff for holding the protector in place.

6. A cuff protector comprising a band adapted to encircle the wrist and be received over the shirt cuff, and a stiffening annulus fixed to the upper edge of said band, said annulus comprising pivoted sections adapted to be swung toward one another and the lower edge of said band, and yieldable means normally swinging said pivoted sections into transverse alinement.

In testimony whereof I have signed my name to this specification.

VOLNEY E. KIRK.
